Term of patent 14 years

(Cl. D67—4)

FIG. 1

FIG. 2

FIGURE 1 is a perspective view of the portable beverage cooler, showing our new design.

FIGURE 2 is a partial sectional view taken substantially on line 2—2 of FIGURE 1.

FIGURE 3 is a perspective view of the portable beverage cooler, shown in one of its operating positions, with the closure member open.

FIGURE 4 is a perspective view similar to that of FIGURE 3 with the closure member shown in the closed position.

FIGURE 5 is a perspective rear view of the portable beverage cooler shown in another operating position.

The louvers and small openings shown partially applied in FIGURES 1, 3, 4 and 5 are intended to cover the entire respective areas encompassed thereby.

The dominant features of the design are shown in solid lines.

We claim:

The ornamental design for a portable beverage cooler, substantially as shown and described.
